MACHINE FOR SPRAY COATING THE
INTERIOR OF CONTAINERSRobert W. Smith, San Carlos, Calif., assignor to
Ferry Sheet Metal Works, Inc., a corporation
of California

Application July 23, 1949, Serial No. 106,400

9 Claims. (Cl. 91—45)

1

This invention relates to machines for applying a coating to the interior surface of a container such as a bread pan, a battery box or the like.

In various industries, it is desirable that the interior surface of a container be adequately covered with a coating composition. For example, in the manufacture of composition to the several compartments of the box to provide added resistance to the sulphuric acid utilized as the electrolyte in the storage battery. In the baking industry, it is usual to apply to the pans a coating of a suitable shortening, grease or the like.

The present invention will be particularly described as it has been successfully employed in the baking industry; however, it is to be understood that it is not limited to this use and that it is capable of general application. The machine of the present invention is particularly characterized in that it enables a uniform coating of a desired weight to be applied to the several surfaces defining an interior cavity in a container, usually a bottom and four sides extending generally vertically. Further, the present invention is characterized in that the device enables a coating composition to be applied successfully and uniformly to the bottom and side walls defining the cavity to be coated without applying the material to the upper edges and to the exterior surface of the container, such application being deemed in the industry unacceptable and unwanted for various reasons.

In general the broad object of the invention is to provide a novel spray coating machine for applying a spray composition to the container walls defining a cavity.

Another object of the present invention is to provide a spraying machine in which containers can be continuously spray-coated.

The invention includes other objects and features of advantage, some of which, together with the foregoing, will appear hereinafter wherein the present preferred form of device of this invention is disclosed.

In the drawing accompanying and forming a part thereof,

Figure 1 is a section taken transversely through a machine embodying the present invention.

Figure 2 is a side elevation showing a portion of the control mechanism utilized.

Figure 3 is a section taken transversely along the run of the conveyor, illustrating the relationship between the spray gun, containers undergoing spraying and the control mechanism.

Figure 4 is a section taken transversely through 55 of handling them.

2

a portion of the control mechanism illustrating the valve structures utilized.

Figure 5 is a schematic showing of some of the apparatus employed and the flow diagram for the air supply.

Figure 6 is sectional view like Figure 1 but showing a modified form of the invention.

Figures 7 and 8 are diagrams illustrating various control systems which can be employed.

Figure 9 is a plan view of another control device.

Figure 10 is a side elevation of the control device shown in Figure 9, additional mechanism being included diagrammatically to illustrate the manner of using this device.

Figure 11 is a side elevation of another form of control device.

Briefly characterized, the present invention includes one or more spray devices suitably positioned to discharge the material to be sprayed into the container; each spray device is fluid-operated and includes means effective upon application of fluid pressure to release fluid for atomizing the material to be sprayed. In accordance with the present invention, the fluid-operating means is operated by a fluid under relatively high pressure so that relatively rapid starting and stopping of atomization is assured. Further, in accordance with this invention, the operation is so regulated that the material sprayed is applied only to the interior of the cavity and not to the exterior surfaces of the walls defining the cavity.

Referring to the drawing, and particularly to Figures 1 and 3, a continuous conveyor generally indicated by numeral 11 is included and comprises two spaced chains 12 movable continuously along rails 13 from left to right in Figure 3 by suitable means which are conventional in the conveyor art and are therefore readily supplied by those skilled in the art. The conveyor 11 moves the containers to be coated, in this instance, bread pan units, generally indicated by numeral 16 and comprising several pans 17 joined together to provide a unit by a strap member 18 which extends along each of the ends of the several pans and along a side of the front and the rear pans. Rails 19 are positioned cooperatively adjacent to the sides of the pan unit 16 to guide the unit during movement by conveyor 11. The several pans in each unit are spaced apart. The units may follow one another when fed into the machine or they may be fed in at irregular intervals. In either case, the machine is capable

The conveyor mechanism so far described is suitably supported as upon a suitable frame structure generally indicated by numeral 21; a housing structure 22 is preferably mounted upon frame 21 and provides an enclosure for presently described spray mechanism. The atmosphere in the housing can be circulated continuously through a filter to avoid release to the atmosphere of grease or solvents, as may be desired.

Mounted upon the housing structure is an adjustable framework 23 including uprights 24 and a cross member 26 upon which are mounted movable brackets 27, each having an arm 28 adjustably retained within a spray gun generally indicated at 29. The spray gun employed is of a type well known in the art and includes a spray nozzle generally indicated by numeral 31 and adapted to spray a fluid supplied under substantially constant pressure and at the requisite temperature through line 32 in atomized form under the pressure of air or other suitable fluid through line 33. The gun includes mechanism adapted to be opened and closed, upon controlled application of high pressure fluid through line 34, to admit or shut off the flow of low pressure atomizing fluid through line 35. In the form of the device illustrated, in Figure 1 a single gun is shown, while in Figure 6 two guns are shown in position; more can be utilized as desired, it only being necessary to supply suitable fluid and air to each of the guns under the control of one of the presently described control mechanism. The gun shown in Figures 1 and 3 includes two spray nozzles 35, each making a spray application to a limited portion of one end wall, the side walls and a portion of the bottom, the areas sprayed by each nozzle overlapping slightly to ensure complete coating.

As is shown particularly in Figure 1, a first control rod 41 extends transversely of the machine and is journaled in bearings 42 and 43. A finger 44 is adjustably secured to the rod 41 and extends upwardly to engage the under side of a bread pan or other container, as it appears in Figure 3. Similarly, a second control rod 46 is provided transversely of the machine and is journaled in bearings 47 and 48, a finger 49 extending upwardly to the same elevation as finger 44 as appeared in Figures 2 and 3, but slightly in advance of finger 44 for reasons which will presently appear.

A lever 51 is secured on one end of rod 41, the extending end of the lever 51 carrying a stud 52 slidably engaged in a slot 53 in arm 55 of bell crank head 54. The bell crank is hinged at 56 and its other arm 58 extends down to operate a valve mechanism generally indicated at 61 and carried in the control unit generally indicated by number 62. Rod 46 includes a lever 63 thereon normally biased in a counterclockwise direction (Figure 2) by a spring 64 and into engagement with valve mechanism 66 in the control unit 62. Each of the valve mechanism 61 and 66 are identical and a description of one will suffice for a description of the other. As is shown in Figure 4, the control unit 62 includes a first cavity 71 in which is positioned a spring 72 carrying a valve member 73, the spring urging the valve member 73 into closing position with respect to a port 74 in a member 76, the latter being positioned at the bottom of a second cavity 77 in unit 62. Member 76 is retained in position by a cage structure 78 provided as an extension upon a threaded member 79 adapted to be screwed into

the unit 62 as a closure for the second cavity. A pin 81 extends through a stuffing gland 82 in the threaded member 79 and into engagement with valve member 73.

Referring to Figure 4, the valve body includes an inlet opening 82 through which air or other high pressure is supplied from a pipe 83, the latter being connected to a pressure regulator 84 which is in turn supplied with fluid from supply 82 by conduit 83; for convenience, air is usually employed and hereinafter will be employed in describing the mechanism and its operation. The inlet 82 in the control unit 62 is connected by a duct 84 to the first cavity 71 associated with the first valve member 61. Air passing through the port 74 and through the openings in the cage 78 is conducted through a duct 86 to the first cavity 71 associated with the second valve member 66 and, under the control of this valve member, through duct 87 to an outlet pipe 88, and thence to line 34 and to the spray gun to control air for spraying. Air for the spraying operation is supplied by line 33 from regulator 84 which is in turn supplied by line 83 from supply 82. In one successful machine, regulator 84 delivered air at 85 pounds per square inch gauge and regulator 86 at 8 pounds per square inch gauge. In this way, rapid release of air for spraying is secured as is the period of spraying.

In operation, line 33 is connected to a low pressure air supply and line 34 in the gun to a high pressure supply under the control of the valve mechanism 62, while line 32 is connected to a suitable supply of the material to be applied to the containers. With conveyor 11 operating continuously and a supply of containers passing more or less regularly through the device, the front edge of a container depresses finger 44 and rocks this in a clock-wise direction in Figure 2; this results in air passage through the line 34 and a spray application to the pan. This continues as long as finger 44 is depressed and until finger 49 is rocked clockwise in Figure 2; when this occurs, valve 66 is closed and the supply of air to the spray nozzle is cut off, even though finger 44 is still depressed. The two fingers 44 and 49 must be spaced apart a distance only sufficient to permit a complete spray application to the selected area of the side walls and the bottom of each container during traverse of each container beneath the spray guns. This distance is related to the width of the bottom of each container with which the fingers are in contact and to the angle at which each spray gun discharges. In the device shown, the spray cut-off occurs while half the container bottom is still to pass over control finger 44. This ensures spray coating of the bottom and the side walls without coating of the rim or outer edges of the container. When the container superimposed over fingers 44 and 49 has moved along to the point where finger 44 is released, finger 49 is still depressed and the spraying cannot occur. However, as soon as finger 49 is released, the mechanism is ready for another spraying application upon rocking of finger 44 in a clockwise direction in Figure 2.

It is possible to control the spray gun in various ways and in Figures 7-11 I have illustrated various apparatus arrangements which can be utilized to secure the required spray coat application and to maintain control of such application with each pan. Referring particularly to Figure 7, I have shown spray gun 29 as supplied with air through line 111, under the control of a solenoid

valve 112, this valve being in turn supplied with air through line 113 under the control of solenoid valve 114 from a suitable source indicated at 116. Solenoid valve 112 is normally open while solenoid valve 114 is normally closed. Valve 114 is controlled by a switch 117 having an actuator arm 118; similarly, solenoid valve 112 is controlled by switch 119 having an actuator arm 121. Each of the actuator arms 118 and 121 is positioned to engage the bottom of a pan on conveyor 11, the switches being supplied with power from lines 122 and 123 to operate the respective solenoid valves.

In operation, with conveyor 11 moving continuously, a pan first engages switch actuator 118 whereby switch 117 is closed and solenoid valve 114 is opened to admit air through line 113, through valve 112 and through line 111 to the spray gun 29. This continues and the spray gun applies a suitable coating to the pan so long as switch 118 is depressed and switch actuator 121 is not engaged; immediately upon the pan bottom engaging the switch actuator 121, solenoid valve 112 is closed to interrupt the supply of air to gun 29, even though the pan is still in a position wherein it is in engagement with switch actuator 118. This insures that the desired area of the pan will be coated, that is, the bottom and the requisite portion of the side wall area.

A similar operation can be secured with the arrangement shown in Figure 8 wherein spray gun 29 is supplied with air from line 131 under the control of a solenoid valve 132 from a suitable source 133. The solenoid valve 132 is placed in series with a switch 134 and a switch 136, the switches being supplied with power from lines 137 and 138. Switch 134 includes an actuator 141, while switch 136 includes an actuator 142; the actuators are positioned to engage successively the bottom of a pan as it is moved along by conveyor 11. Switch 134 is normally open when the actuator 141 is in the raised position, while switch 136 is normally closed when the actuator 142 is in its raised position. Thus, as conveyor 11 moves a pan along, the pan will engage actuator 141 and close switch 134 whereupon current will be supplied to open the solenoid valve, switch 136 being normally closed. The supply of air will be discontinued immediately upon actuation of actuator 142 and the opening of switch 136.

Referring particularly to Figures 9 and 10, a switch 151 is provided to control the supply of power from lines 152 and 153 to solenoid valve 154, the latter controlling the supply of air from source 156 to line 157 to spray gun 29. Switch 151 includes an actuator rod 158 which is normally biased to move upwardly.

The switch includes a bracket 161 mounted on the side thereof and having a rod 162 extended between the ends of the bracket. A first member 164 is mounted upon the rod 162, the member 164 being bifurcated and having two arms 168 which extend horizontally from a vertical, pan-engaging portion 167. Mounted between the spaced arms 168 is another pan-engaging member 168, the latter being mounted on rod 162. A spring 169 is extended between member 164 and member 168, its force being applied in such direction that the horizontal portions of members 164 and 168 are normally in the same plane. The end of the switch actuator 158 rides on the horizontal portion of member 168.

In operation, the switch actuator 158 and the pan-engaging members 164 and 168 are normally in the full line position shown in Figure 10 and the switch is open. Upon a pan engage-

ing the first pan-engaging member 164, the entire switch actuator is depressed, spring 169 being of sufficient strength to rock pan-engaging member 168 simultaneously with the counterclockwise rotation of pan-engaging member 164 about rod 162. As the pan movement continues, member 168 is engaged and rocked clockwise and, since the switch actuator 158 is in engagement with the pan-engaging member 168, the switch actuator is permitted to move upwardly to open the switch and discontinue the supply of air to the spray gun 29.

Referring to Figure 11, I have shown another modified form of the device and which includes a valve casing 171 having a slidable valve element 172 therein and which is moved by an arm 173 from a suitable solenoid (not shown). The valve casing includes a closure 174 at one end thereof, a spring 176 being placed between this closure and the slidable valve 172. At the other end of the body, a closure 177 is provided and includes an air escape aperture or passage 178, controlled by a needle valve 179. Air to be supplied to the spray gun is admitted through conduit 181 and passage 182 in the valve body to an outlet passage 183 which is connected to the spray gun; an exhaust passage 184 is provided and is connected to the spray gun by a passage 186 in the valve body.

In operation, the solenoid for moving the arm 173 is energized momentarily, as by a switch placed in the path of a pan and which switch is closed to move the solenoid arm to the left in Figure 11. This brings passage 182 into alignment with the air supply passage 181 and the spray gun passage 183, whereby air is supplied to the spray gun. Upon de-energization of the solenoid, spring 176 becomes effective to force the valve to the right in Figure 11 against the slow escape provided by the controlled outlet through passage 178. The air escape through passage 178 is regulated to permit of the application of air to the spray gun for the desired period of time. Upon cessation of the spraying operation, the residual air trapped in the gun and in the line to the gun is released through passage 186 and exhaust port 184.

From the foregoing, I believe it will be apparent that I have provided a novel and simple spraying device which can be quickly adapted to the spraying of various containers and which enables a spray application to be made selectively, for example, to those interior surfaces defining the cavity in the container, such as in a bread pan.

This is a continuation in part of my application Serial No. 38,498, filed July 13, 1948, and now abandoned.

I claim:

1. In a device of the character described, means for spraying a material under pressure at a spraying station to apply said material to a predetermined uniform area at said station, a conveyor movable past said station for transporting a series of objects each having an exposed area to be sprayed corresponding substantially to said predetermined uniform area, means for supplying a material to be sprayed to said spraying means, means for supplying air at a first pressure to said spraying means to spray said material in atomized form, air operated means controlling release of air to said spraying means, means for supplying air under a second pressure relatively great with respect to said first pressure to said air operating means, a first control means

independently operated by an object on said conveyor to release the high pressure air to said air operating means, and a second control means spaced a relatively short distance beyond said first control means in the direction of advance of said conveyor and independently operated by an object on said conveyor while in engagement with said first control means to cut off release of the high pressure air to said air operating means.

2. In a device of the character described, means for spraying a material under pressure at a spraying station to apply said material to a predetermined uniform area at said station, a conveyor movable past said station for transporting a series of objects each having an exposed area to be sprayed corresponding substantially to said predetermined uniform area, means for supplying a material to be sprayed to said spraying means, means for supplying air at a first pressure of about 8 pounds per square inch gauge, to said spraying means to spray said material in atomized form, air operated means controlling release of air to said spraying means, means for supplying air under a pressure of about 85 pounds per square inch gauge to said air operating means, a first control means independently operated by an object on said conveyor to release the high pressure air to said air operating means, and a second control means spaced a relatively short distance beyond said first control means in the direction of advance of said conveyor and independently operated by said object on said conveyor while said object is in engagement with said first control means to cut-off release of the high pressure air to said air operating means.

3. In a device of the character described, means for supplying air under a first elevated pressure, means for spraying a material in atomized form at a spraying station, pressure reducing means for delivering air from said air supply means to said spraying means at a second pressure less than said first pressure, control means operated by air under said first pressure for controlling a supply of air under said second pressure to said spray means, a conveyor movable over a path including said spraying station to transport a series of uniformly sized objects to be sprayed past said station; means for supplying air under said first pressure to said control means including a conduit between said air supply means and said control means and including a first valve and a second valve arranged serially in said conduit with an outlet of said first valve connected directly to an inlet of said second valve, means biasing the first valve to closed position, means biasing the second valve to open position, a first means for engaging an object on said conveyor during traverse thereof toward said spraying station to open the first valve, and a second means for engaging an object on said conveyor during traverse thereof along said path to close the second valve while said first valve is in engagement with said object, said second means being spaced a short distance from said first means in the direction of advance of the conveyor.

4. In a device of the character described, means for supplying air under a first elevated pressure, means for spraying a material in atomized form at a spraying station, pressure reducing means for delivering air from said air supply means to said spraying means at a second pressure less than said first pressure, control means for said air supply to said spraying means operated by air under said first pressure, a con-

veyor movable over a path including said spraying station to transport a series of uniformly sized objects to be sprayed past said station; and means for supplying air under said first pressure to said control means including a conduit between said air supply means and said control means and including a first valve and a second valve arranged serially in said conduit with an outlet of said first valve connected directly to an inlet of said second valve, means biasing the first valve to closed position, means biasing the second valve to open position, a first control element in the path of an object on said conveyor for opening said first valve upon engagement with an object, and a second control element for closing said second valve and spaced from said first control element a relatively short distance in the direction of advance of the conveyor.

20 5. In a device of the character described, means for supplying air under a first elevated pressure, means for spraying a material in atomized form at a spraying station, pressure reducing means for delivering air from said air supply means to said spraying means at a second pressure less than said first pressure, control means for said air supply to said spraying means operated by air under said first pressure, a conveyor movable over a path including said spraying station to transport a series of uniformly sized objects to be sprayed past said station; and means for supplying air to said control means including a conduit between said air supply means and said control means and including a first valve and a second valve arranged serially in said conduit, means biasing the first valve to closed position, means biasing the second valve to open position, a first control element in the path of an object on said conveyor for opening said first valve upon engagement with an object and for maintaining said first valve open during such engagement, and a second control element adjacent to said first control element and in the path of an object on said conveyor engaged with said first element for closing said second valve and for maintaining said second valve closed during only a portion of the engagement of said first control element with said object.

6. In combination, means for spraying a material, a conveyor movable over a path to transport articles serially past said spraying means, means for supplying air to the spraying means for spray application of a material onto said articles, and means for controlling the supply of air to the spraying means and comprising an air supply for energizing said spraying means, a first first valve means biased toward closed position and a second valve means biased toward open position, said valves being arranged serially with said first valve interposed in said air supply ahead of said second valve to have an outlet of said first valve connected directly to an inlet of said second valve, a first control element for opening the first valve means upon engagement of said first control element with an object on said conveyor, and a second control element for closing the second valve means upon engagement of said second control element with said object during at least a portion of the engagement of said first control element with said object, said second control means being spaced from said first control means a relatively short distance along the path of the conveyor.

7. In combination, means for spraying a ma-

terial, a conveyor movable over a path to transport articles serially past said spraying means, means for supplying air to the spraying means, and means for rendering the spraying means effective to spray material onto an object moved past the spraying means by said conveyor and comprising a first control means effective to energize said spraying means upon and during engagement of said first control means with said object during movement of said object past said spraying means, and a second control means effective to de-energize said spraying means during energization thereof by said first control means upon and during engagement of said second control means with said object during movement of said object past said spraying station, said second control means being spaced from said first control means a relatively short distance along the path of the conveyor.

8. In a device of the character described, a conveyor movable over a path including a spraying station, spray means at said station to apply spray material to a predetermined uniform area at said station, control means for said spray means including a first valve and a second valve connected in series with an outlet of said first valve connected directly to an inlet of said second valve, said control means controlling flow of an actuating fluid to said spray means through a conduit, the second valve being normally open and the first valve being normally closed, a first means for opening the first valve when said first means is engaged by an object moving past said station and having an exposed area to be sprayed corresponding substantially to said predetermined uniform area, and a second means for closing the second valve, said second means being spaced a relatively short distance from said

first means in the direction of advance of said conveyor for engaging an object moved by the conveyor while said object is in engagement with said first means.

- 5 9. In a device of the character described, a conveyor movable over a path including a spraying station, spray means at said station to apply spray material to a predetermined uniform area at said station, control means for said spray means including a first valve and a second valve connected in series with an outlet of said first valve connected directly to an inlet of said second valve, said control means controlling flow of an actuating fluid to said spray means through a conduit, the second valve being normally open and the first valve being normally closed, a first means engaged by an object moving past said station for opening the first valve, and a second means engaged by an object during and following engagement thereof with said first means for closing the second valve, said second means being spaced from said first means a relatively short distance in the direction of advance of said conveyor.
